UNITED STATES PATENT OFFICE.

ALBERT BOUWERS, OF EINDHOVEN, NETHERLANDS, ASSIGNOR TO N. V. PHILIPS' GLOEILAMPENFABRIEKEN, OF EINDHOVEN, NETHERLANDS.

X-RAY TUBE AND INSTALLATION FOR OPERATING THE SAID TUBE.

Application filed August 25, 1925, Serial No. 52,345, and in the Netherlands March 25, 1925.

This invention relates to X-ray tubes and to an installation for operating same. In such installations a high tension transformer is frequently employed, the primary winding of which is connected to a source of low tension. As a rule these transformers occupy much space and are rather expensive. It is known that for operating X-ray tubes high frequency currents may be utilized, in which case a transformer without iron can be used.

It has now been found that it is possible to combine a transformer at least partly with the X-ray tube to form a unitary device without the X-ray tube thereby becoming more difficult to manipulate.

According to this invention, around an X-ray tube is wound a coil the ends of which may be electrically connected to the cathode and the anticathode, said coil being adapted to permit a high tension current to be generated therein. In addition the X-ray tube may be provided with a second coil which surrounds the other coil and serves to generate the high tension. If now the X-ray tube is operated with a tension of high frequency, the secondary winding may consist of a small number of turns.

For operating X-ray tubes according to the invention, the use of high frequency currents, however, is not absolutely necessary.

According to the invention, in order to permit the operation of these X-ray tubes with lower frequency currents, an iron core is arranged along the axis of the X-ray tube inside the secondary coil wound on the wall of the X-ray tube. For this purpose, if necessary, a cavity may be provided in the anticathode along the axis of the X-ray tube, or the iron core may be arranged in the interior of the anticathode tube. It has been found that X-ray tubes constructed in this manner can be operated with currents having a frequency of, for example, 500 periods.

Instead of using a source of current of high frequency, it is also possible to periodically interrupt the primary current supplied by a source of continuous current or alternating current of lower frequency, with the aid of an interrupter. If the interruption takes place very rapidly, the same effect is produced as in the case of high frequency currents.

The invention will be more clearly under-

stood with reference to the accompanying drawing.

An incandescent cathode 2 in the form of a stretched wire is arranged within a metal vessel 1 which may be made of chrome iron forming part of the envelope of the tube and to the wall of which is secured a metal cover 3 having an aperture in front of which is arranged an anticathode 4, part of whose surface is opposite this aperture. In the metal vessel opposite the said anticathode is a window for the passage of the X-rays generated. This window consists of a glass hood 5 which is hermetically sealed to the metal wall. An annular metal plate 6, for example of iron, serves to screen the X-rays and has secured to it the leading-in wires for the incandescent cathode. One leading-in wire 7 for the incandescent cathode is led through the metal ring 6 from which it is insulated, and is sealed into the glass hood 5. The other leading-in wire is constituted by the conductive connection of a pole 8 with the metal ring 6 and by the metal envelope 1. The cathode rays emitted by the incandescent cathode can strike the anticathode only on a limited surface owing to the particular shape of the wall and of the cover 3 of the metal vessel, and to the arrangement of the anticathode relatively to the said cover. To the metal vessel 1 is sealed a re-entrant glass tube 9 to the end of which is sealed the anticathode 4. Around the upper end of the anticathode is arranged a cooling device 10.

Around the glass part of the wall of the X-ray tube is wound a coil 11 which at one of its ends is connected to the metal vessel 1 and thus is electrically connected to the incandescent cathode and which at its other end is in conductive connection with the anticathode. Around this coil 11 is provided a second coil 12 which is separated from the former by means of a layer 13 of insulating material. The ends of the coil 12 can be connected to a source of high frequency tension consisting, for example, of an oscillatory circuit in which high frequency oscillations are generated by means of a transmission tube as used for radiotelegraphic purposes. It is evident, however, that the high frequency oscillations may be generated in any other known manner as by a spark gap or by means of an arc. If,

for example, the coil 11 consists of a single layer of 500 turns and if the coil 12 contains 10 turns, the tension of the tube generated by the secondary winding will be, for example, 50,000 volts of the source of high frequency furnishes a tension of 4000 volts and the frequency corresponds to a wave length of 10,000 metres.

It must be borne in mind that a good functioning is only assured if the primary and secondary oscillatory circuits are almost tuned to each other. For this purpose it will be necessary therefore to choose the natural oscillations of these circuits such that they are almost equal to each other.

Although the invention has been described with reference to a tube of cylindrical shape it is evident that it can also be applied to X-ray tubes of any other shape.

20 What I claim is:

1. An X-ray tube characterized in that around the tube is wound a coil the ends of which are electrically connected to the cathode and to the anticathode, said coil being adapted to permit a high tension current to be generated therein.

2. An X-ray tube according to claim 1, characterized by a second coil which surrounds the other coil and serves to generate 25 the high tension.

3. An X-ray tube, characterized in that around the tube is wound a coil, the ends of which are electrically connected to the cathode and to the anticathode, said coil being 35 adapted to permit a high tension current to be generated therein, an iron core being arranged inside said coil about the axis of the X-ray tube.

4. An X-ray tube according to claim 3, characterized by a second coil surrounding 40 the other coil and serving to generate the high tension.

5. An X-ray tube, characterized in that around the tube is wound a coil the ends of which are electrically connected to the 45 cathode and to the anticathode, said coil being adapted to permit a high tension current to be generated therein, an iron core being arranged inside said coil in the interior of the anticathode tube.

50 6. An X-ray tube according to claim 5, characterized by a second coil which surrounds the other coil and serves to generate the high tension.

7. An X-ray tube installation comprising 55 an X-ray tube, a coil being wound around said tube, the ends of said coil being electrically connected to the cathode and to the anticathode, said coil being adapted to permit a high tension current to be generated 60 therein, a second coil surrounding the other coil and being fed by a source of rapidly varying tension.

8. An X-ray installation according to 65 claim 7, an iron core being arranged inside the first coil about the axis of the X-ray tube.

9. An X-ray tube installation according to claim 7, an iron core being arranged inside the first coil in the interior of the anti- 70 cathode tube.

In testimony whereof I affix my signature, at the city of Eindhoven, this first day of August 1925.

ALBERT BOUWERS.
